AIR FLOW CONVEYER

Frederick John Cherewick, Vancouver, British Columbia, Canada

Application December 20, 1948, Serial No. 66,350

4 Claims. (Cl. 302—50)

1

My invention relates to improvements in air flow conveyors, the object of which is to provide means for delivering comminuted fuels or other granular materials from one place to another.

The invention as here to be described is primarily designed for use in delivering sawdust into bins in homes from a delivery truck, where it is necessary to pile the sawdust up to substantially ceiling height and well into corners, so that available space shall be made the utmost use of.

A further object is to provide means whereby the delivery shall be rapid and continuous, to reduce the cost of delivery, and also to deposit the sawdust delivered in its final storage position with a minimum amount of fine dust being left in suspension in the air surrounding the end of the delivery hose.

The invention contemplates the use of a Venturi structure wherein one component of the structure delivers a propelling media to the other and the other component of the structure delivers material free from air or vapour entrainment into the propelling media, as will be more fully described in the following specification and shown in the accompanying drawings, in which—

Figure 1 is a longitudinal sectional view of the invention.

Figure 2 is an enlarged sectional view of the outer end of the screw conveyor.

Figure 3 is a transverse sectional view taken on the line 3—3 of Figure 1.

In the drawings like characters of reference indicate corresponding parts in each figure.

The numeral 1 indicates a base which is adapted to be mounted on or within a delivery truck. Mounted upon the base 1 is a horizontally disposed cylindrical pipe 2 having a fuel inlet opening 4, to which is fitted a suitable hopper 5 for feeding the sawdust or other material to the pipe 4. Fitted around the pipe 2 is a circular air feed housing 6 having an annular row of outlet orifices 7 in one wall which communicate with a Venturi cone 9. The air housing 6 is connected with a blower 11 which is driven from the power take-off of the truck, not shown, or from any other source of power.

A delivery pipe 12 of substantially the same diameter of the cylindrical pipe 2 extends from the truncated end of the cone 9 and in alignment with said pipe 2 and is spaced from the pipe 2 to form an annular Venturi jet 14. To the outer end of the pipe 12, one or more lengths of pipe or metallic flexible hose 16 are adapted to be connected, which would obviously extend to a point close to the desired place of delivery of the sawdust.

2

Rotatably mounted within the cylindrical pipe 2 is a feed screw 18 having a shaft 19 which is journalled in spaced bearings 20 carried by the base 1. The outer end of the shaft 19 is splined or otherwise provided to slidably but non-rotatably engage a pulley 21 by which the feed screw 18 is driven from a suitable source of power. A block 24 is slidably fitted into the mouth of the cylindrical pipe 2 and the shaft 19 is held against movement therealong by the collars 25. The block 24 is fitted with a lug 26, see Figures 1 and 2, in which the shaft 28 of a hand screw 29 is journalled, the screw 29 threadedly engages a lug 30 which is carried by the outer end of the pipe 2. The conveyor shaft 19 is, by means of the hand screw 29, adjustable endwise of the pipe 2, so that the inner end of the feed screw 18 may be adjusted to any desired distance away from the annular Venturi jet 14, or the inner end of the pipe 2.

In operating the device, sawdust is run into the hopper and the feed screw 18 is set in motion to build up a plug 35 of compressed sawdust at its inner end, the blower 11 is set in motion to create a force of air at the Venturi jet of suitable pressure. The plug 35 of compressed sawdust at the discharge end of the pipe 2 is thrust beyond the end of the pipe towards the inner end of the pipe 12, reducing to some extent the interspace of the annular jet 14 therebetween. The restriction of said interspace causes a momentary increase in air velocity which disintegrates parts of the plug back to comminuted material and assists or causes masses of the plug to break off and enter the pipe 12 which as already described is aligned with the pipe 2 and is of the same diameter. These masses may be only slightly less than the diameter of the pipe 14 and naturally are thrown thereinto under the influence of the higher velocity air from the jet. Each mass remains as a loosely fitting plunger for a short distance of travel and is carried at substantially wind velocity through the pipe and into the hose 16 where it too breaks down to comminuted material substantially filling the pipe and traveling therethrough at air speed, which soon levels off to a constant. The intermittent movement of the plug to reduce the air jet and the breaking off of plug masses to restore it to normal, causes a fluttering action at the entrance to the pipe 14 so that a great volume of sawdust is entrained by the air flow. In actual practice, this machine being supplied with air to the cone 9 at a pressure of five pounds p. s. i. and fitted with a delivery pipe 12 and hose 16 of four inches diameter will deliver six tons of sawdust in ten minutes with-

out clearly visibly creating a dust laden atmosphere two feet beyond the delivery end of the hose. The air flutter at the annular jet is believed to be the reason that the sawdust is carried into the pipe 12 in a dense mass and is capable of being entrained in an air stream of but little greater volume than that combined with the sawdust before feeding it into the hopper. The object of building up the plug of compressed sawdust in the pipe 2 to the rear of the annular jet 14, is also to prevent air from entering the delivery pipe 12 from the feed hopper.

It will be obvious that adjustment will need to be made to the machine to compensate for the type of material to be conveyed and the distance or height to which it must be conveyed. For instance, with light material to be delivered a short distance only, the plug 35 would not need to be of great length and the volume of air required to be delivered through the jet 14 would be low. If the distance of delivery were to be increased, the air flow from the blower would need to be increased and the screw 18 drawn back by the hand screw 29 to provide a longer plug 35 and so prevent air flow lengthwise of the screw 18.

What I claim as my invention is:

1. A conveyor for comminuted material comprising a cylindrical pipe and a delivery pipe in axial alignment, said pipes being spaced apart to define an annular jet, a feed hopper intermediate the length of the cylindrical pipe, a feed screw extending lengthwise of the cylindrical pipe and terminating short of the jet to define an unobstructed cylindrical space wherein material

acted upon by the feed screw will compress into a substantially self supporting solid cylindrical body, the diameter of the portion of the cylindrical pipe between the end of the feed screw and the jet being constant and being equal to the diameter of the end of the feed screw, said cylindrical pipe and delivery pipe being of the same diameter adjacent the annular jet, and means for admitting air under pressure through the annular jet.

5 2. In a device as claimed in claim 1, said air admitting means including a conical housing surrounding said cylindrical pipe and in communication with the annular jet, and means for admitting air to the housing.

15 3. In a device as claimed in claim 2, means exterior of the cylindrical pipe for moving the feed screw lengthwise of the pipe.

20 4. In a device as claimed in claim 1, means exterior of the cylindrical pipe for moving the feed screw lengthwise of the pipe.

FREDERICK JOHN CHEREWICK.
